UNITED STATES PATENT OFFICE

HARRY C. RIDLER, OF MINNEAPOLIS, MINNESOTA

AIR WASHER AND HUMIDIFIER

Application filed May 19, 1930. Serial No. 453,545.

My present invention relates to a device for washing and humidifying the air in a room or building and has for its main object the provision of an extremely simple, highly efficient and relatively inexpensive device of the kind described.

Generally stated, the invention consists of the novel devices, combinations of devices and arrangement of parts hereinafter described and defined in the claims.

In the accompanying drawings, which illustrate the invention, like characters indicate like parts throughout the several views.

Referring to the drawings:

Fig. 1 is a plan view of one form of the device and showing a portion of the floor of a building, some parts of the device being broken away and some parts being shown in section;

Fig. 2 is a section taken on the line 2—2 of Fig. 1;

Fig. 3 is a section taken on the line 3—3 of Fig. 2;

Fig. 4 is a view partly in side elevation and partly in axial section in a somewhat modified form of the device, some parts being broken away;

Fig. 5 is a fragmentary section taken on the line 5—5 of Fig. 4;

Fig. 6 is a view in side elevation of another slightly modified form of the device, some parts being broken away;

Fig. 7 is a section taken on the line 7—7 of Fig. 6;

Fig. 8 is a section taken on the line 8—8 of Fig. 7;

Fig. 9 is a section taken on the line 9—9 of Fig. 7; and

Fig. 10 is a plan view of the water containing dust sediment pan.

Referring first to the form of the device shown in Figs. 1 to 3 inclusive wherein the floor of a building is indicated by the letter "y". The numeral 10 indicates a casing that is provided at its upper portion with a grille or the like 11. This casing 10 is adapted to project through an opening 12 in a floor "y" and to be suspended from the floor, as illustrated, with its grilles portion at approximately floor level. Within the casing 10 is

an air heating means 13, preferably in the form of a tubular steam or hot water radiator, comprising a tubular inner wall 14, and a tubular outer wall 15 spaced apart to afford an annular heating medium circulating chamber 16 therebetween and a humidifying chamber 15a therein. The annular chamber 16 is closed at its ends and adapted to be connected to a suitable source of heat, such as a hot water or steam boiler, through heating medium circulating connections 17 that project through the casing 10 and open through the outer wall 15 of the radiator. The tubular radiator 13 is removably supported in the casing 10 by casing cross-members 18 that are engaged by lugs 19, carried by the outer shell of the radiator. The bottom of the casing 10 is normally closed by a removable water-retaining dust-collecting pan 20, extended through and above the bottom of which is an overflow pipe 21, which overflow pipe carries away all water in excess to a desired predetermined level and most of the dirt washed from the air.

By reference to Fig. 1, it will be noted that the casing 10 is just wide enough to accommodate the tubular radiator 13 and therefore, said radiator forms the intermediate portion of a partition that extends between opposite ends of said casing 10. The bottom portion of this partition structure, below the radiator 13, is formed by an approximately half-round skirt 22 that is carried by and depending from the outer lower portion of the radiator and the upper portion of this partition structure is formed by a hood-like member 23 and a partition member 24 that is carried by the top of the hood 23 and extends vertically therebetween and the grille 11 and transversely the full width of the casing.

The hood 23 is formed with a depending annular collar portion 25, that fits within the inner shell 14 of the tubular radiator, see Figs. 1 and 2. Also by reference to said figures, it will be noted that the portion of the hood-like member 23, above the tubular radiator and to the right of the axis of said radiator, is widened to meet the sides of the casing 10. Depending from the projected right-hand end portion of the hood 23 and

extending between opposite sides of the casing 10 and terminating above the water level in the pan 20, is a baffle partition 26.

The interior of the casing 10 is divided, 5 as described, to form a U-shaped air intake duct 27, at the right-hand side of the casing, and an air discharge duct 28, at the left-hand side of the casing. The U-shaped air intake duct 27 directs air downwardly from the 10 half of the grille 11 thereabove between the baffle 26 and the right-hand side of the casing 10, close to the water level in the pan 20, under the baffle and upwardly between said baffle and the right-hand outside of the tubular radiator and into the top of the air washing and humidifying chamber 15^a. The air duct 28 directs air, passed downward through the chamber 15^a, upward between the left-hand side of the tubular radiator and the 15 casing 10 to and through the portion of the grille 11 and thereabove to the atmosphere.

In the air duct 27, under the hood 23 and axially centered in respect to the chamber 15^a, is a spray nozzle 29, which nozzle is 20 adapted to project a conical or inverted funnel-shaped spray downwardly axially into the chamber 15^a. This spray nozzle 29 is connected to receive supply water under pressure from a suitable source through a supply line 30 and either or both of two supply line branches, to wit: a branch line 31, interposed in which is a flow regulating shut-off valve 32, and a branch supply line 33, interposed in which is a heat-receiving coil 34 25 and a flow regulating shut-off valve 35.

The heat-receiving coil 34 is contained within the annular heating medium circulating chamber 16 of the tubular radiator and the stems of the valves 32 and 35 are operable manually from above the grille by a detachable key or the like 36, indicated by dotted lines in Fig. 2, the key being inserted through the grille and into operative engagement with the valve stems.

45 It will, of course, be understood that when the valve 35 is closed and the valve 32 is open, supply water will be delivered to the spray nozzle at ordinary supply water temperature but when the valve 32 is closed and the valve 50 35 is open, the supply water will be delivered to the nozzle through the heat-receiving coil 34. If heating medium is being circulated through the annular circulating chamber 16 of the radiator, in a hot condition, heat therefrom will be absorbed by the water, in the coil 34, and warm or hot water will be delivered to the spray nozzle 29. Also if the valves 32 and 35 are each partly open, a mixture of cold and hot water may be delivered 55 to the spray nozzle and by making the proper adjustments of said valves, the desired spray temperature can be maintained. When heat medium is circulated through the annular heating medium circulating chamber 16 of the radiator and the water supply

to the spray 29 is connected through either or both of the regulating valves 32 or 35, the operation will be as follows: Cold air, near the floor of the room, which, of course, has a natural tendency to settle, will pass 70 downwardly through the right-hand side of the grille 11 and through the right-hand portion of the air duct 27, between the baffle 26 and side of the casing 10, and will reverse its direction of travel and pass under the baffle 75 26 and upwardly between said baffle and the right-hand side of the tubular radiator where it will become heated by said radiator and be caused to rise toward the top of the air duct 27 into the hood-like portion 23. 80

It should now be understood that the downwardly projected conical or inverted funnel-shaped spray, from the nozzle 29, will cause a down draft in the humidifying and air washing chamber 15^a, which will cause the 85 intake air to pass downwardly through the chamber 15^a and into the air duct 28 where said air will become further heated by the left-hand outside portion of the radiator and be caused to rise quite rapidly and pass outward through the left-hand side portion of the grille. The conical spray projected from the spray head 29 fills the entire humidifying and air washing chamber and, 90 therefore, all air passed through the humidifier is necessarily passed through the fine spray. Part of this mist-like spray will, of course, be absorbed by the warmed air, which is circulated therethrough and the balance thereof will condense and drip into the water-containing dust sediment pan 20 and will maintain the water level in said pan at the desired level determined by the distance the overflow pipe 21 is projected above the bottom of said pan and, of course, the excess 95 water will be drained off through the overflow pipe 21. Of course, air taken from the ordinary room contains considerable undesired dust, smoke etc. Dust or heavier than 100 air particles, passed downwardly into the air duct 27, will have a tendency to fall by gravity into the water-containing sediment pan 20 at the bottom of said duct when the air reverses its direction of travel and thus the air will be subjected to a primary cleaning by means of gravity separation. Lighter particles of dust and smoke will, of course, be passed into the humidifying and air washing chamber 15^a and passed through the 105 spray and upon passing through the spray, smoke will become condensed therein and dust particles and such foreign matter will 110 become soaked and the weight of the water will cause the same to drop into the sediment 115 pan 20, below the chamber 15^a, and only very thoroughly purified air will be returned to the atmosphere through the air duct 28. It will, of course, be necessary at intervals to 120 remove the pan 20 and clean out the sedi- 125

130

ment that does not wash out through drain pipe 21.

The amount of humidity or moisture absorbed by the air passed through the chamber 15^a will be dependent mainly upon two factors: first, the amount of heat radiated from the tubular radiator and absorbed by the passing air and second by the temperature of the supply water delivered to and projecting from the spray nozzle 29. Assuming that the heating medium circulating connections 17 to the radiator are connected to receive heat from the water or steam boiler that is used to heat the room in which the humidifier is used, the first factor, to wit: the amount of heat applied to and radiated from the tubular radiator will be automatically taken care of and will vary according to the amount of heat required to heat the room or building under various weather conditions. Therefore, on a cold day, when a great deal of heat is required to properly heat the room or building, the tubular radiator will become much hotter than it would on a relatively warm day when very little heat is required to heat the building or room and consequently the amount of moisture which the air is caused to absorb will, to a great extent, be automatically governed by the amount of heat required to heat a building under varying weather conditions so that on a cold day the air in the room will be caused to absorb much more moisture than it will on a warm day when little or no heat is necessary. It is, of course, well understood that warm or hot air will absorb a great deal more moisture than will cool or cold air so, therefore, the more heat applied to the air by the tubular radiator, the greater will be the absorption of moisture by the air. It is desirable in order to maintain, under different weather conditions, approximately the same degree of humidity to apply more moisture to the air in a heated room in cold weather than in warm weather for in cold weather the outside atmosphere contains very little moisture and when brought to a high temperature in a room or building a very dry warm air condition exists.

The first factor, therefore, governing the amount of humidity absorbed by the air is controlled automatically but it is desirable to provide some means of regulating each device to suit the particular installation and this I preferably accomplish by regulating the second noted factor, to wit: the temperature of the water delivered to and projected from the nozzle 29, this being accomplished by means of the valves 32 and 35 as previously described. A warm or hot finely atomized spray water will, of course, be absorbed by the air much more rapidly than a cool or cold spray.

I have found that the most satisfactory results are obtained when a somewhat over-

sized air washing and humidifying device is employed, that is, to say, a device capable of supplying more than the desired amount of humidity to the air at a maximum adjustment when all of the supply water to the nozzle is delivered thereto through the coil 38 and therefor at a relatively high temperature and then after the installation by means of valves 32 and 35, mix the hot and cold supply water before delivery to the nozzle to cut down the humidity to the desired extent. It should here be noted that while the velocity of air passed through the intake and discharge air duct and chamber 15^a is materially vacillated by heat passed off by the tubular radiator, the down draft, created by the spray in the chamber 15^a, is in itself sufficient to maintain a circulation of air through the air washer and humidifier. The device will, therefor, continue its operation as an air washer even when the heat is turned off. The form of device thus far described, as shown in Figs. 1 to 3 inclusive, is especially adapted for domestic use in homes and the like because of its quiet operation and its inconspicuous out of the way position below the floor.

Referring next to the slightly modified form of the device shown in Figs. 4 and 5, which device is adapted to set on the floor in the room in which it operates. This device is also adaptable for domestic use where there is ample space for the same in the room in which it is used but it is especially adapted for use in relatively small offices, factories and the like. In Figs. 4 and 5, parts corresponding to parts in Figs. 1 to 3 inclusive are indicated by like characters.

The numeral 37 indicates the casing of the device, 38 indicates a grilled opening in the top of the casing, 39 an air intake duct leading through one side of the lower portion of the casing 37 to the top of the tubular radiator, and 40 a discharge air duct leading from the lower portion of the air washing and humidifying chamber 15^a to the atmosphere through the grille 38. The bottom of the casing 10 is removable and forms a water-retaining dust-collecting pan 41, below the humidifying and air washing chamber 15^a and air duct 40. The entire casing and parts contained therein are supported above the floor on legs 41^a. In this form, like in the form first described, the casing is just wide enough to accommodate the tubular radiator and said radiator, the skirt 22, and the hood-like member 23 form a partition structure between opposite sides of the casing. In this form, however, the air is taken in at the bottom of the casing and the entire grille, above the casing, is used for discharging all air. In this form of device, the heating medium circulating pipes 17 and water supply pipe 31 are projected upwardly through the floor beneath the casing and through the air duct 40.

39 so that they are substantially concealed from view. The valves 32 and 35 in this instance have their stems projected through one side of the casing and said stems are 5 provided through one side of the casing and said stems are provided with operating handles 42.

In the inlet opening of the inlet air duct 39 is a motor driven fan 43 which, when 10 operated, will draw air from the room and force the same through the air duct 39, into and through the chamber 15^a, to and through the air duct 40 to the atmosphere. The air 15 washing and humidifying action accomplished in this form will be substantially the same as that described for the form shown in Figs. 1 to 3 inclusive. In this form the motor 43 may be dispensed with and the 20 natural draft or circulation of air created by the combined action of heat and the action of the spray may be depended upon. By use of the motor, however, the capacity of the device is considerably increased for the reason that a more rapid movement of air will 25 be created.

Referring next to the slightly modified form of the device shown in Figs. 7 to 10 inclusive wherein certain parts like those shown in other figures are indicated by like characters. The air washing and humidifying action of the device presently to be described is very similar to the action of the devices previously described, but the casing and arrangement of inlet and outlet air ducts are 30 somewhat different and are especially adapted for relatively large devices for use in large buildings for supplying washed humid air to a large or several smaller rooms. The tubular radiator, in this instance, is contained 35 within a casing comprising a water containing dust sediment pan 44, a casing member 45 and opposed channel-like casing members 46. The sediment pan 44 is approximately 40 the width of the tubular radiator but is considerably longer than it is wide. This pan 44 is provided, near its longitudinal center, with a top plate 47, on which the tubular radiator is seated and in the center of which top plate 47 is an opening 48 that aligns 45 with the air washing and humidifying chamber 15^a of the tubular radiator. The member 46 is in the form of a pan that is closed 50 at its top and open at its bottom.

The pan 45 is of just sufficient width to 55 receive the tubular radiator but is sufficiently longer than the diameter of the tubular radiator and higher than the tubular radiator to form air ducts 49 that open near the top of and beyond the sides of the pan 44 and lead 60 upwardly past opposite sides of and above the tubular radiator, which radiator acts as a partition member between opposite sides of the pan-like casing member where they connect together and to the top of the air 65 washing and humidifying chamber 15^a. The

pan-shaped casing member, as shown in the drawings, is telescopically over the tubular radiator and seated upon the projecting end portions of the dust-collecting pan 44. The 70 channel-shaped casing members 46 are each secured to the opposite side of the pan-like casing member 45 at 50 and at the bottoms said channel-shaped members are removably attached to the dust-collecting pan 44 at 51. The channel-shaped members 46 form outlet 75 air ducts 53.

In this form of the device, the stems of the valves 32 and 35 are projected through the top of the pan-like casing member 45 and the heating medium circulating pipes 17 and 80 water supply pipe 30 are brought upward through the floor and into the air ducts 49. Telescopically fitting and leading from each of the air outlet ducts 53 and forming a continuation thereof is a branch 54 of a large 85 clean humidifying air delivery pipe 55. This air delivery pipe 55 may lead either to one of the large rooms or, if desired, by providing a multiplicity of smaller delivery branches from the delivery pipe 55 several 90 rooms may be supplied with clean humid air.

Mounted on the delivery pipe 55 is a fan or air blower 56 that has its delivery tube 56^a projected into said pipe 55. This tube 56^a opens in the direction of the air flow through 95 the pipe 55. When the fan or blower 56 is operated, a blast of air will be projected into and through the pipe 55 toward its outlet end, which will cause a vacuum therebehind that will pull air from the atmosphere surrounding the air washing and humidifying device upwardly through the ducts 49, downwardly through the air washing and humidifying chamber 15^a and upwardly through outlet ducts 53, to and through the delivery pipe 55 thus producing a rapid circulation of air 100 through the device.

While it is highly desirable to use a fan or blower to produce a rapid circulation of 110 air through the air washing and humidifying device and thereby materially increase its capacity the device, like the other devices previously described, will function without the use of a fan, if desired. For example, 115 if the fan or blower 56 is not used, air, in the ducts 49, will become heated by the tubular radiator and be caused to rise into the top thereof above the air washing and humidifying chamber 15^a, the downwardly projected spray will create a down draft that will cause the air to be moved downwardly through the air washing and humidifying chamber to the dust-collecting sediment pan 44 and pass outwardly into the outlet ducts 53 where it 120 will become further heated and be caused to rise into and through the delivery pipe 55.

The air washing and humidifying action of this form of device being substantially like that of the forms previously described, 125 130

no further description and operation is thought necessary.

What I claim is:

1. A device of the class described comprising a chamber that is open at its ends and surrounded at its sides by an air-heating means, a water supply, a nozzle connected to the water supply and arranged to project a spray longitudinally into said chamber, and means for pre-heating the supply water before delivery to said nozzle.

2. In a device of the class described, a radiator comprising tubular inner and outer walls spaced to afford an annular heating medium circulating chamber therebetween and a humidifying chamber within said tubular radiator, a spray nozzle arranged to project a spray longitudinally into said humidifying chamber, a water supply line for said nozzle, and a heating coil in said annular heating medium circulating chamber, and adapted to be connected in said nozzle water supply pipe for pre-heating water before it is projected into the humidifying chamber.

3. A device of the class described comprising a humidifying chamber, a heating means surrounding said chamber, a nozzle arranged to project a spray downwardly into said chamber, and a water-containing sediment pan below and spaced from the bottom of said chamber.

4. The structure defined in claim 3 in further combination with an air duct arranged to direct air, downwardly through said chamber and upwardly past the outside of said heating means.

5. A device of the class described comprising a humidifying chamber an air-heating means surrounding said chamber, an air duct arranged to direct air upwardly past the outside wall of said air-heating means and deliver the same to the top of the humidifying chamber, an air duct arranged to direct air downwardly through said chamber and upwardly past the outside wall of said air-heating means to the atmosphere, and a spray nozzle arranged to project a spray of water downwardly through said humidifying chamber.

6. The structure defined in claim 5 in combination with a water-containing dust sediment pan below said chamber.

7. The structure defined in claim 5 in further combination with a power-driven fan for circulating air through said ducts and chamber.

8. The structure defined in claim 5 in combination with a removable sediment pan below and spaced from the bottom of the humidifying chamber, and a drain therefor opening above the bottom of said pan to carry away excess water which collects the dirt and carries it away.

9. In a device of the class described a hu-

midifying chamber that is open at its upper and lower ends, air heating means surrounding said chamber, a spray nozzle arranged to project a spray of water downwardly into said chamber, and an air duct leading from the lower end of said chamber and upward past the outside of said air heating means.

10. In a device of the class described a humidifying chamber that is open at its upper and lower ends, a radiator surrounding said chamber, an air duct for delivering incoming air upwardly past the outside of said radiator to the top of said chamber, and a spray nozzle arranged to direct a spray downwardly into said chamber.

11. In a device of the class described a humidifying chamber that is open at its upper and lower ends, a radiator surrounding said chamber, an air duct for delivering incoming air upwardly past the outside of said radiator to the top of said chamber, a spray nozzle arranged to direct a spray downwardly into said chamber, a water supply line leading from said nozzle, means for heating the supply water in said line before delivery to the nozzle by the heating medium circulated through said radiator, and means for regulating the amount of heat supply to the water before delivery to said nozzle.

12. In a device of the class described, a tubular radiator comprising a tubular inner wall affording an intermediate chamber therein and a tubular outer wall spaced from said tubular inner wall to afford an annular heating medium circulating chamber therebetween, a spray nozzle arranged to project a spray longitudinally into said chamber, branch water supply lines to said nozzle, a heat receiving coil within the annular heating medium circulating chamber and interposed in one of said branch water supply lines, and a valve interposed in each of said supply lines for regulating the temperature of water delivered to said nozzle.

13. A device of the class described comprising an upright humidifying chamber, heating means surrounding said chamber, and a spraying nozzle located axially of said humidifying chamber and constructed and arranged to project a spray of water outwardly against the upper portion of the inner wall of said chamber whereby the water contacting with said wall will run downwardly and much thereof will be evaporated, said chamber being open at its bottom, and means below said chamber for catching the surplus or unevaporated water.

In testimony whereof I affix my signature.

HARRY C. RIDLER.
